John Harvey

United States Patent Office.

JOHN M. HARVEY, OF BUCHANAN, VIRGINIA.

Letters Patent No. 72,489, dated December 24, 1867.

IMPROVEMENT IN STEAM-GENERATORS.

The Schedule referred to in these Letters Patent and making part of the same.

TO ALL WHOM IT MAY CONCERN:

Be it known that I, JOHN M. HARVEY, of Buchanan, in the county of Botetourt, in the State of Virginia, have invented a new and improved Steam-Boiler; and do hereby declare that the following is a full and exact description thereof, reference being made to the accompanying drawings, and to the letters of reference marked thereon.

The nature of my invention consists in the construction and arrangement of the herein-described steam-generator.

To enable others skilled in the art to make and use my invention, I will proceed to describe its construction and operation.

It consists in placing a boiler with a convex bottom immediately over another boiler with a concave top or upper side, having a space of two and a half feet between them, when the boilers are not more than thirteen feet in length. The boilers are connected by vertical pipes, or semicircular ones, as may be preferred. A wall of fire-brick closes up the apparatus at the sides. This wall is built so as to leave an opening between it and the boilers, sufficient to let the flame permeate over and around the lower boiler, except the grate-head, and on the upper to the water line, (see drawing A.) The lower boiler is made shorter than the upper the depth of the grate. An opening is made in the wall, in or near to the centre of the concave boiler, eight by four inches, for the purpose of admitting atmospheric air at the point of the greatest combustion, and is used for observing the action of the flame, and regulating it, (see B in drawing.) The end of concave boiler next the chimney is depressed to receive the regulator, formed out of soapstone, from two to three feet in length. This regulator is operated by a wheel and shaft. On the latter is placed a short arm, and on the wheel a chain, which extends to the fireman at the grate, by which the draught is increased or diminished, and by which a complete reverberation is effected, (see C in drawing.)

What I claim as my invention, and desire to secure by Letters Patent, is—

The construction and arrangement of the within-described steam-generator, in a manner substantially as shown.

JNO. M. HARVEY.
